UNITED STATES PATENT OFFICE

2,259,617

BRASSIÈRE

Lena M. Clermont, Washington, D. C.

Application December 16, 1939, Serial No. 309,665

1 Claim. (Cl. 2—42)

My invention relates to new and useful improvements in women's under-garments, and more particularly to a brassière.

One of the objects of the present invention is to produce a brassière that will hold in the diaphragm and hold up the breasts and thus prevent them from sagging on the diaphragm.

A further object of the invention is to produce a brassière that will tightly snug the diaphragm of the wearer, prevent the breasts from sagging, and give the effect of what is known as a wasp-like waist.

Another object of the invention is to provide a brassière that extends below the breasts and engages and pulls in the diaphragm to thus produce a wasp-like waist and at the same time cups the breasts to produce what is known as the "up-lift" feature.

Still another object of the invention is to produce a brassière that is reinforced centrally in the front with stays to assist in holding in the diaphragm, prevent the brassière from wrinkling, and at the same time hold the breasts firmly in position above the diaphragm.

Still another object of the invention is to produce a brassière that is relatively simple to make, as the parts may be quickly assembled and sewed by a skilled operator on a sewing machine.

Still another object of the invention is to provide a brassière, the ends of which at the back of the wearer are provided with adjustable holding means while the front of the brassière is provided with stays and the usual corset fastening, so that after the brassière is once adjusted to the body to firmly hold in the diaphragm and cup the breasts, the brassière may be fastened and unfastened from the front of the wearer, thus simplifying the action of putting on and taking off the brassière.

With these and other objects in view, the invention consists in certain new and novel features and combination of parts, as will be hereinafter more fully explained and pointed out in the claim.

In the drawing,

Fig. 1 is a perspective view of my new garment as it would appear on the form;

Fig. 2 is a rear view of the brassière as opened up for purposes of illustration; and

Fig. 3 is a section along the lower marginal edge thereof.

Referring now more particularly to the several views, and for the moment to Fig. 2, there is shown my new and improved brassière, which may be made of any light, strong, durable cloth,

and when in its open position comprises the base or body 1, which is relatively wide and is adapted to encircle the diaphragm of the wearer to pull the same in to give the waist of the wearer a wasp-like effect. This body portion is made of two like sections 2 and 3 while the ends 4 and 5 extend around to the back of the wearer and are provided with buckles 6 and straps 7, so that the circumference of the girdle may be adjusted within certain limits. Of course, the brassière will also be made in different sizes.

On the inner adjacent ends of the sections 2 and 3 are provided the cooperating stays 8, which are provided with the usual cooperating hooks 15 and studs 9. Thus, after the length of the brassière is once regulated, the brassière thereafter is to be fastened or unfastened by simply moving the stays slightly with relation to each other, so that the studs become engaged or disengaged from the eyes in the usual manner.

It will be noticed that the lower marginal edge 10 of the brassière when opened up extends in a substantially horizontal line and will extend just below the chest or diaphragm of the wearer. The upper marginal edges of the brassière extend in a slightly curved line toward the center, as shown at 11 and 12, respectively, the greatest depth of the brassière being the points just slightly remote from the vertical stays centrally of the garment or, in other words, about centrally of the breasts. Each section (and a description of one is a description of the other) is also provided with a pleat 13, which tends to gather the material of the body section below the upper marginal edge and the stitching 13' of the pleat extends up to the points 14 to form the resultant gores 15 to thus provide a looseness of material, as illustrated, as it is this looseness of material plus additional pieces that form the pockets for the breasts.

There is also an overlap and line of stitching, as at 16, which occur under the arms when the garment is on the wearer, so that the whole garment will smoothly throughout its width tightly snug the diaphragm of the wearer.

Referring to the section 2 (and it will be remembered that a description of one section is a description of the other), there may be seen the additional piece of material 18, which is stitched along its base 19 directly above the gores 15, while extending from the apex of this triangular additional piece of material may be seen the strap 20, which fastens to the upper marginal edge of the section 2, as at 21.

This piece is duplicated as heretofore men-

tioned with a like piece 18' and the shoulder strap 20' on the section 3.

It will be seen that by providing the stays 8 on the two sections so that they extend centrally of the diaphragm of the wearer and right between the breasts, the base or body of the brassière will be prevented from becoming wrinkled or drawn up throughout its width. Also, the pleats and their stitching will reinforce the garment as well as provide a fullness and permit 10 gores directly beneath each breast.

Ordinary brassières have a tendency to fold or compress transversely when used but by providing the pleats and stays, this is prevented in the present garment.

Furthermore, by having the body portion of the brassière relatively tight around the diaphragm of the wearer and prevented from sagging, the cup portions on the marginal edge will hold the breasts from sagging, while the additional pieces will also cover the breasts. Then the garment as a whole is further prevented from sagging by the shoulder straps, which are fastened as shown to the back of the garment.

From the foregoing, it will be seen that I have provided a relatively wide brassière that may be pulled tightly about the diaphragm of the wearer to thus give the appearance of a small waist. I have also provided means to prevent a folding or wrinkling of the garment when on the wearer, so that the breasts may be well supported in the upper marginal edges of this tight-fitting diaphragm-encircling brassière.

Also it will be seen that the brassière is one that may be readily manufactured, as after the 35 pieces are once cut to shape, the pleats are quick-

ly stitched and the gores formed above the stitching, after which the two additional triangular portions may be stitched in place and then the straps and buckles, etc. readily attached. Of course, the edges are bound to also strengthen the garment and provide a finishing appearance.

Many slight changes are possible in the construction hereinbefore set forth without in any manner departing from the spirit and scope of the invention.

Having thus described my invention, what I claim as new and desire to secure by Letters Patent is:

A brassière comprising a body portion of relatively great depth but adapted to terminate about the body of the wearer above the waist line, said body portion comprising two similar main portions and two similar triangular upper portions, each of said upper triangular portions attached to a main portion along a transverse line substantially centrally of the breasts of a wearer, stiffening means along the front vertical edges of said main portions carrying fasteners for detachably securing said main portions, the upper ends of said stiffening means terminating at the upper marginal edges of said main portions, each of said main portions having pleats each of which extends parallel to said stiffening means, the lower portion of said pleats being closed by stitching and the upper portion being open to provide a fullness below said transverse line, shoulder straps secured to the apices of said triangular portions and said main portions and means for fastening together the rear edges of said main portions.

LENA M. CLERMONT.
